MORSE CODE HAND SIGNALING DEVICES
Charles L. Cleek, Los Angeles, Calif.
(1540 Sagebrush Road, Palm Springs, Calif.)
Filed Sept. 14, 1959, Ser. No. 839,880
4 Claims. (Cl. 340—366)

The present invention relates to Morse code hand signaling devices, and is directed more particularly to that type employing battery power for energizing the light source.

An object of the present invention is to provide a compact, simple, lightweight construction of relatively few moving parts which can be assembled and disassembled even by children.

Another object of the present invention is to provide a device somewhat resembling signal lamps employed upon marine-type vessels for the training of signalmen.

A further object of the present invention is to provide a signal device of the character described which may be used on hiking trips and on lakes for signaling between boats and shore.

With the foregoing and other objects in view, the invention will be more fully described hereinafter, and will be more particularly pointed out in the claims appended hereto.

In the drawings, wherein like symbols refer to like or corresponding parts throughout the several views:

FIGURE 1 is a perspective view of a hand signaling device constructed in accordance with the present invention shown in the hand of a user with the shutters in the open position;

FIGURE 2 is a bottom perspective view of a device constructed in accordance with the present invention with the shutters in the closed position;

FIGURE 3 is a front elevational view looking into the device with the shutters in the closed position;

FIGURE 4 is a vertical section taken on the line 4—4 in FIGURE 3;

FIGURE 5 is a transverse section taken on the line 5—5 in FIGURE 4;

FIGURE 6 is a longitudinal section taken on the line 6—6 in FIGURE 4;

FIGURE 7 is a view similar to FIGURE 4 with the shutters shown in the open position and the light source in the energized position, and

FIGURE 8 is a fragmentary perspective view of the shutter actuating mechanism having parts broken away and parts shown in section illustrating the normally biased closed positioning means of the shutter mechanism.

Referring now to FIGURES 1 through 3 inclusive, 10 designates generally a cylindrical light housing closed at one end as at 10^a and having a shutter closure device 11 at its other end. Shutters 12 are pivotally mounted in the shutter cover assembly 11. Depending from the cylindrical light housing 10 is a pistol-type hand grip 13 which cooperates with a pivotally mounted trigger 14 which is positioned to be engaged by the index finger 15 of the hand 16 of the operator. Secured at the top of the cylindrical light housing 10 is an inverted U-shaped side member 17.

Referring now to FIGURES 4 through 8 inclusive and for the moment to FIGURE 5, it will be noted that the shutters 12 are pivoted to the shutter assembly as at 18. Secured to and extending from each shutter 12 are tongues 19 which are pivotally connected to a shutter operating rod 20. The shutter operating rod 20 has at its lower end a projection 20^a extending off at substantially right angles thereto which is positioned to be engaged by a forward extension 14^a of the trigger 14. The trigger pivots about a pivot 14^b.

2

Located approximate the rear or closed portion 10^a of the cylindrical housing 10 is a battery 21 of the flashlight or dry type. Support members 22 are provided in the housing at the rear portion thereof and are provided with cutouts 23 to accommodate the battery 21 to properly position the same.

Located between the shutter closure member 11 and the battery 21 is a polished reflector 24 of the conventional flashlight type having a screw socket base for receiving a conventional flashlight bulb 25 therein.

The circuitry between the lamp 25 and the battery 21 in the form of the invention illustrated and as best seen in FIGURES 4 and 7, comprises a conductive path of metallic material 26, one end of which is secured to the rear of the reflector and adapted to be placed in electrical connection with the outer portion of the socket of the lamp 25 and the other end of which is adapted to be resiliently biased or urged into contact with one of the terminals of the flashlight battery 21. The other leg of the circuit 10 between the center contact of the base of the lamp 25 and the battery 21 is provided by means of a metallic path of the conductive material 27 which is secured to, but insulated from, the reflector 24, and a portion of which is positioned to be engaged by a projection 14^c of the trigger 14 whereby upon rotation of the trigger 14 about the pivot 14^b, the projection 14^c will urge the conductive material 27 into physical and electrical contact with the other pole of the battery 21 to thereby complete the circuit between the lamp 25 and battery 21 causing illumination 15 of the lamp.

As best seen in FIGURE 8, the shutter 12 whose tongue 19 is pivotally connected to the operating rod 20 is biased to a normally closed position by a helical spring 28 carried by the pivot, one end of which 28^a engages the operating rod 20 while the other end 28^b engages the tongue 19.

In operation, the battery 21 is first placed in the housing 10 in the manner shown in FIGURE 4 and the reflector and lamp assembly 24, 25 is then placed in position. It will be noted that the lower portion of the reflector assembly is slotted to permit movement of the portion 14^a of the trigger. The closure cover 11 is then placed on the open end of the cylindrical housing 10 in such a manner that the forward extension 14^a of the trigger 14 lies over and is positioned against the right angle extension 20^a of the shutter operating rod 20 whereby upon squeezing the trigger 14, the forward portion of the trigger 14^a rocks in a counterclockwise direction pulling the shutter operating rod 20 downwardly causing the shutters to open, as best seen in FIGURE 7. The origin position of the trigger in this figure is shown in dotted lines as are the shutters.

Simultaneously with this opening of the shutter mechanism, the projection 14^c engages the resilient strip of conductive material 27 and urges same into contact with the battery 21 to complete the circuit between the battery and the lamp, whereby a source of light emitted from the lamp will be viewable through the open shutters from the front end of the device. Each time the trigger is released, the resiliency of the helical springs 28 will cause the shutter operating rod to be elevated to the position of FIGURE 4, closing the shutters and simultaneously breaking the electrical contact between the battery 21 and the strip of resilient conductive material 27.

When the device is properly assembled, the lamp 25 cannot be energized unless the shutters 12 are open.

Although I have disclosed herein the best form of the invention known to me at this time, I reserve the right to all such modifications and changes as may come within the scope of the following claims.

What is claimed is:

1. A hand signaling device comprising a receptacle having one end thereof open, a light source in said receptacle, normally open circuit means for energizing said light source comprising a source of energy, normally closed shutter closure means mounted in the light path between said light source and the open end of said receptacle, a pistol grip depending from said receptacle, a trigger being mounted on said pistol grip, and means operatively connected with said trigger for simultaneously closing said circuit means and opening said shutter closure means to thereby simultaneously energize said light source and open said shutter closure means.

2. A hand signaling device as claimed in claim 1 wherein said shutter closure means comprises a plurality of shutters positioned one above the other in overlapping relationship and each of which is connected to a common operating rod having a helical spring between each shutter and the rod for biasing the shutters to the normally closed position and which rod is provided at its base with means positioned to be engaged by the trigger whereby upon squeezing of the trigger the shutters are swung to the open position.

3. The device of claim 1, said source of energy being a battery carried in said receptacle.

4. A hand signaling device as claimed in claim 1, wherein a reflector is provided in said receptacle, said light source being electrically and mechanically connected with said reflector, and wherein said normally open circuit means comprises a strip of resilient material extending between the reflector and one pole of the battery and wherein the other element is a strip of resilient conductive material extending between the lamp and the other pole of the battery, being positioned to be engaged by the trigger upon squeezing thereof to close the circuit whereby the lamp is energized.
